UNITED STATES PATENT OFFICE

HARRY A. RHINEVAULT, OF CHICAGO, ILLINOIS, ASSIGNOR TO CHARLES D. KARR,
OF HOLLAND, MICHIGAN

RESILIENT CUSHION

Application filed April 18, 1927. Serial No. 184,453.

This invention relates to resilient cushions. An object of the invention is to provide a cushion made up of a plurality of coiled springs arranged in a plurality of parallel rows and wherein the individual springs of each row are connected at their opposite sides to the springs in adjacent rows by simple means which prevent relative displacement of the individual springs with reference to each other and said connecting means.

A more particular object of the invention is to provide a cushion wherein the opposite ends of each coiled spring are formed with rings having diametrically outwardly disposed off-sets, with the terminal ends of the wires forming the spring disposed inwardly beneath the rings and also provided with an off-set in alignment with one of the off-sets of the ring, whereby the terminal ends co-operate with the rings to provide two thicknesses of material for co-operation with connecting means which secure the coiled springs together and aid in preventing relative movement of said coiled springs with respect to said connecting means.

Still another object of the invention is to provide a cushion of the character referred to in which the coiled springs are so arranged as to dispose the two thicknesses of wire at each end thereof of each spring in juxtaposition with reference to the single thickness of wire of a spring in an adjacent row, whereby three thicknesses of wire are presented at the points of the coiled springs engaged by the connecting means throughout the body portion of the cushion, and wherein each row forming the outside or border row of the cushion is formed by reversing the positions of the coiled springs so that the two thicknesses of wire are presented along the margin of the cushion, and the springs of the marginal row have their inner side comprising a single thickness, disposed adjacent the single thickness presented by the springs of the next row.

Other and further objects of the invention will more clearly and fully appear from the description and claims hereinafter following.

In the drawings forming a part of this

specification, Figure 1 is a broken top plan view of a cushion embodying my invention. And Figure 2 is an enlarged vertical sectional view taken through the cushion substantially upon the line 2—2 of Figure 1. As shown in the drawings, 10 indicates an outside or marginal row of coiled springs, 11 indicates a row of coiled springs disposed next to the marginal row 10, while 12 indicates a plurality of intermediate rows of springs, and 13 indicates a marginal row disposed opposite the marginal row 10, as many intermediate rows 12 being provided as desired, depending upon the width of the cushion.

Each of the rows 10, 11, 12 and 13 is made up of a plurality of coiled springs indicated at 14, arranged in spaced relation as shown, and as many springs 14 may be included in the various rows as desired, depending upon the length of the cushion it is desired to construct. All of the coiled springs 14 are of exactly similar construction, but are arranged in a particular manner to provide an efficient type of cushion as hereinafter described.

Each of the coiled springs is made up of resilient wire of suitable gauge, and comprises an intermediate body portion, the opposite sides of which are concave as shown, the intermediate portion including a plurality of helical turns of wire indicated at 15, while the top and bottom ends of each coil are formed in circular rings or annuli 16 and 17 disposed substantially at right angles to the longitudinal axis of the coil, and the terminal ends of the wire are indicated at 18 and 19, each of the ends 18 and 19 being disposed inwardly of the ring members 16 and 17 as shown, so that the ends of the coil do not project outwardly of the plane defined by the rings 16 and 17. Each of the rings 16 and 17 is provided with diametrically disposed off-sets 20 and 21, and the terminal ends 18 and 19, are provided with off-sets indicated at 22 disposed in alignment with the off-set 21 in each ring. The marginal row 10 of the cushion is made up of a plurality of the springs 14 of the character described with the two thicknesses of wire provided by one side of the ring, and the terminal end of the wire, disposed outwardly as best shown

at the right-hand portion of Figure 2, thereby presenting only a single thickness of wire inwardly toward the remaining rows of the cushion. The springs of the row 11 are reversed so as to present a single thickness of wire at the top and bottom of the coil in juxtaposition with reference to the single thickness presented by the rings of the marginal row 10, thereby presenting a double thickness of each spring of the row 11 inwardly. The springs 14 which go to make up the adjacent intermediate rows 12 are disposed with the single thickness of the rings in juxtaposition with reference to the double thickness presented by the coiled springs of the row 11, and each of the successive rows 12 are disposed in the same manner so as to present three juxtaposed thicknesses at the adjacent top and bottom ends of the springs forming the rows 12, until the opposite marginal row 13 is reached. The springs of the row 13 are oppositely disposed with reference to the springs of the marginal row 10, so as to present two thicknesses of the springs outwardly, while the single thickness is disposed inwardly in juxtaposition with reference to the single thickness of the next intermediate row 12 of the cushion.

Connecting members indicated at 23, 24, 25, connect the various rows of coiled springs together at the top and bottom ends. Each of the connecting members comprises a small coiled wire which at the outer side of the marginal row 10 is threaded through the off-sets 21 and 22 in the rings 16 and 17 and the terminal ends of the coil, as best shown in Figure 1, the connecting member serving to secure the various springs comprising the row 10 together, and securing the terminal ends of the spring in positions on the inner sides of the rings, the inter-engagement of the connecting members with the off-sets in the terminal ends and rings of the coiled springs preventing rotation of the springs with reference to the connecting members and preventing displacement of the springs. The connecting member 24 is of a character similar to the connecting member 23 and connects the off-sets 20 of the springs of the rows 10 and 11, only two thicknesses of wire being disposed within the coils of the connecting member at this point, but the off-sets preventing relative displacement of the springs of the rows 10 and 11. The connecting member 25 is similar to the connecting member 24 and the coils of the connecting member are interengaged with the off-sets 21-22 and 20 of the rows 11 and 12 of the springs, and by reason of the disposition of said springs, three thicknesses of wire are placed within the coils of the connecting member at the points of connection of the springs comprising the rows 11 and 12. The next successive rows 12 will have the springs disposed in the same manner as the rows 11 and 12, and in

each instance at the connecting points between the rings of the springs, three thicknesses of wire will be presented and engaged within the loops of the connecting members, providing an important advantage in eliminating any possibility of the coiled springs moving with reference to each other and to said connecting means. The opposite marginal row 13 is affixed to the last of the intermediate rows 12 in the same manner as the springs of the row 10, the two thicknesses being presented outwardly, while the single thicknesses of the springs forming the row 13 and the next intermediate row are secured together as before described.

By the above described arrangement it will be appreciated that due to the disposition of the terminal ends of the coils, said ends are held beneath the rings thereof when the connecting members are in position, and due to the formation of the off-sets in both the terminal ends of the springs and the rings, at all points in the cushion, except at the marginal edges thereof, three thicknesses of material are embraced by the coils of the connecting member, absolutely preventing any possibility of relative displacement of the coiled springs with reference to each other and said connecting means, and additionally by reason of the reversal in position of the springs forming the marginal rows 10 and 13, two thicknesses of material are presented at the marginal edges of the cushion for inter-engagement with the coils of the connecting members, thereby providing means for preventing relative displacement of the coiled springs of the marginal rows with reference to the connecting members.

While I have herein shown and described what I consider the preferred manner of carrying out the invention, the same is merely illustrative, and I contemplate all changes and modifications which come within the scope of the claims appended hereto.

I claim:

1. In a cushion of the character described, the combination with a plurality of rows of spaced coiled springs, each of said springs having an annulus at its opposite ends, and a terminal portion co-operating with each annulus to provide a double thickness of material at one portion thereof, each annulus being provided with diametrically disposed off-sets, and said terminal portion being provided with an off-set in alignment with the adjacent off-set in the corresponding annulus; and connecting means for securing the coiled springs of said row together, said connecting means including a connecting portion disposed about the plurality of off-sets in the annulus and in the terminal portions of each pair of springs in adjacent rows, said terminal portions being secured by said connecting means inwardly of the material forming the annulus portions of said spring,

and said connecting portions being also connected together.

2. In a cushion of the character described, the combination with a plurality of marginal and intermediate rows of coiled springs, each of said springs having an annulus at each end, and a terminal portion co-operating with said annulus to provide a double thickness of material at one portion of each annulus, the double thickness of the springs forming the marginal rows being disposed outwardly and the single thickness being disposed inwardly, and the springs of the rows adjacent the marginal rows having the single thickness disposed toward the marginal rows, and other intermediate rows having the single thickness of the springs forming one row disposed in juxtaposition with reference to the double thickness of the springs forming the corresponding adjacent row; connecting means in the form of coiled members, one of said connecting means having loops thereof disposed about the double thicknesses of the coils forming the marginal rows, the connecting member for the springs of the marginal row and the row next to said marginal row having loops disposed about the juxtaposed single thicknesses thereof; and the connecting members for the intermediate rows, and the rows next to the marginal rows having loops encircling three thicknesses of material, and means for engaging said connecting means for preventing rotation of said springs.

3. In a cushion of the character described, the combination with a plurality of marginal and intermediate rows of coiled springs, each of said springs having an annulus at each end, and a terminal portion co-operating with said annulus to provide a double thickness of material at one portion of each annulus, the double thickness of the springs forming the marginal rows being disposed outwardly and the single thickness being disposed inwardly, and the springs of the rows adjacent the marginal rows having the single thickness disposed toward the marginal rows, and other intermediate rows having the single thickness of the springs forming one row disposed in juxtaposition with reference to the double thickness of the springs forming the corresponding adjacent row; and connecting means in the form of coiled members for connecting the springs of the same and adjacent rows together, one of said connecting means having loops thereof disposed about the double thicknesses of the coils forming the marginal rows, the connecting member for the springs of the marginal row and the row next to said marginal row having loops disposed about the juxtaposed single thicknesses thereof; and the connecting members for the intermediate rows, and the rows next to the marginal rows having loops encircling three thicknesses of material.

material, the juxtaposed thicknesses of the springs forming the various rows being provided with off-sets for the reception of the loops of the connecting means.

4. In a cushion of the character described, the combination with a plurality of marginal and intermediate rows of coiled springs, each of said springs having an annulus at each end, and a terminal portion co-operating with said annulus to provide a double thickness of material at one portion of each annulus, the double thickness of the springs forming the marginal rows being disposed outwardly and the single thickness being disposed inwardly, and the springs of the rows adjacent the marginal rows having the single thickness disposed toward the marginal rows, and other intermediate rows having the single thickness of the springs forming one row disposed in juxtaposition with reference to the double thickness of the springs forming the corresponding adjacent row, said annuli of the springs being provided with distorted portions; and connecting means in the form of coiled members for engaging said distorted portions to prevent rotation of said springs, one of said connecting means having loops thereof disposed about the double thicknesses of the coils forming the marginal rows, the connecting member for the springs of the marginal row and the row next to said marginal row having loops disposed about the juxtaposed single thicknesses thereof; and the connecting members for the intermediate rows, and the rows next to the marginal rows having loops encircling three thicknesses of material, the terminal portions of the annulus at each end of each spring being disposed upon the inner side of the material forming the annulus, and held in position by said connecting means.

5. In a spring assembly for cushions and the like, a plurality of spiral springs arranged in rows, each spring having an annular portion and a terminal portion arranged adjacent to a similar annular portion of a spring of an adjacent row, one of said portions being provided with a distorted section, and a plurality of longitudinally extending helical springs encircling said portions and said sections of the springs in adjacent rows of said assembly whereby the coils of said helical will embrace three thicknesses of spring material, thereby preventing clicking of said assembly during the use thereof.

In witness that I claim the foregoing I have hereunto subscribed my name this 15th day of April, 1927.
